UNITED STATES PATENT OFFICE.

CLARENCE L. TAYLOR, OF ALLIANCE, OHIO, ASSIGNOR TO THE MORGAN ENGINEERING COMPANY, OF ALLIANCE, OHIO.

APPARATUS FOR FINISHING CAR-WHEELS.

1,302,880.

Specification of Letters Patent. Patented May 6, 1919.

Application filed May 29, 1917. Serial No. 171,684.

To all whom it may concern:

Be it known that I, CLARENCE L. TAYLOR, a citizen of the United States, and a resident of Alliance, in the county of Stark and State of Ohio, have invented certain new and useful Improvements in Apparatus for Finishing Car-Wheels; and I do hereby declare the following to be a full, clear, and exact description of the invention, such as will enable others skilled in the art to which it appertains to make and use the same.

My invention relates to an improvement in apparatus for finishing car wheels, and it consists in a series of rolls adapted to engage the periphery or tread and sides of a wheel blank and roll the latter into its final or finished shape.

It also consists in details of construction as will be more fully described and pointed out in the claims.

In the accompanying drawings, Figure 1 is a view partly in plan and partly in section of my improved rolling mill; Fig. 2 is a front end view of the same; Fig. 3 is a view in section on the line A—A, of Fig. 1 and Fig. 4 is a view in section on the line B—B of Fig. 1.

1 represents the base or frame of the machine, provided near its front end with brackets 2, separated sufficiently for the introduction of a wheel blank 3 between them, the adjacent faces of said brackets having horizontal slots in which the mandrel 4, carrying the wheel blank 3 is supported, the horizontal slots permitting the mandrel to move outwardly as the rolling of the wheel blank progresses.

The wheel blank 3 after having been formed, centered and punched, is placed on the centering mandrel 4, and the latter mounted in the slotted brackets 2, after which the driving rolls 5, which are shaped, as more clearly shown in Fig. 4, are moved into contact with the wheel blank 3 at the rear of the rim of the wheel blank as shown in Fig. 1.

The driving rolls 5 which shape the rear of the rim of the blank, or wheel 3, are fast on the shafts 6, which are mounted in bearings 7 in the carriers or housings 8. These housings which are constructed as shown in Figs. 1 and 4, are pivotally mounted at their rear ends on the posts 9, which are firmly secured in recessed seats 10 in the base or frame 1, and the said housings rest on the

upper face of the base or frame 1 as shown in Fig. 4, and are held down onto said frame, by the bent flanges 11 on the frame 1 engaging the groove 12 in the front end of the housing. Each carrier or housing has a limited movement in the arc of a circle concentric with the posts 9, and each is moved by a screw 13, mounted in an internally threaded nut 14 carried by the brackets 15 integral with the frame 1. These brackets 15 form bearings for the shafts 16 which are continuations of the screws 13, and each shaft is provided with a pinion 17 which meshes with a smaller and wider pinion 18. Pinion 18 is made wider than pinion 17 so as to permit of the necessary longitudinal movement of the shafts 16 and its pinion 17, and the shaft of pinion 18, carries pinion 19 which meshes with small pinion 20 on shaft 21. Shaft 21 carries the larger pinion 22 which meshes with small pinion 23 on armature shaft 24 of the motor 25. By starting motors 25, the shafts 16 will be rotated slowly, and by reason of their screw threads will also be moved longitudinally, which latter movement in one direction, forces and holds the rolls 5 in contact with the wheel blank 3, while a reverse movement withdraws the screws and moves the carriers or housing outwardly so as to disengage the rolls from the wheel blank, thus permitting of the removal of a finished wheel and the insertion of a blank. The screws 13 have a loose or swivel connection at their ends with the carriers, so that the reverse rotation of the screws will positively pull the carriers outwardly away from the wheel 3, and the drive motors for the two screws are coupled or connected and actuated by a single switch or controller so that uniform movement of the two screws will always be maintained.

Keyed to each shaft 6 is a bevel gear 26 which meshes with a larger idle bevel gear 27 loosely mounted on the post 9. The two bevel gears 27 are driven by the bevel gears 28 fast on the main drive shaft 29 which latter is supported in bearings 30 on the frame 1.

The bevel gears 27 are arranged horizontally on the base, that is with their axes vertical, and serve as idler gears through which the power is transmitted from the driving gears 28, to the gears 26 on shafts 6, and they are separated on a line parallel with the position of the wheel blank 3, so

that the normal position of the main rolls 5 is at about an angle of sixty degrees to each other, and they operate as before explained to shape and compress the blank at the under or inner side of the rim or tread.

The face or tread of the wheel blank is shaped by the roll 29^a, best shown in Fig. 3. This roll 29^a is mounted in the carrier 30^a, which is journaled at the lower end on the bearing 31 so as to permit the roll to be moved toward and away from the wheel blank 3, the construction being such that the carrier is securely guided laterally in the main frame 1. The housing 30^a is connected by link 32 with the front end of the screw shaft 33, the said shaft being supported and also guided at its front end by the bearing 34. The threaded end of the shaft 33 engages the internal threads of the nut 35, which latter is journaled in the bearing 36 formed in the frame 1, and projects at the rear to receive the pinion 37 which is keyed to the end of the nut. This pinion 37 meshes with the small pinion 38 on shaft 39, which latter carries the larger pinion 40 which meshes with smaller pinion 41 on shaft 42. Pinion 43, keyed to shaft 42, meshes with the small pinion 44 on the armature shaft 45 of the motor 46.

The tread roll 29^a is constructed at its periphery, to form and impart final shape to the tread and flange of the wheel, and it is forced and held in contact with the wheel blank 3, by the gearing described. The rolls 5 act as an abutment or stop against the pressure exerted against the blank 3 by the roll 29^a, and the latter in turn acts as a stop for the pressure of the rolls 5 against the underside of the rim. The roll 29^a is free to revolve in its housing, hence as the wheel blank 3 is rotated by the positive rotation of the rolls 5, the roll 29^a will be revolved against the tread of the wheel by its frictional contact with the latter.

47 are the guide rolls, which operate to hold the blank 3 in proper position with relation to the rolls 5 and 29^a, and also roll the two sides of the tread of the wheel blank. They are located as shown in Fig. 3, underneath the driving rolls 5 and close up to the latter and are journaled on the eccentric ends 48 of spindles 49 which are mounted to turn in the obliquely arranged bearings 50, formed in the frame 1.

Shaft 53, passes from one end of the frame 1 over the two spindles 49, and is provided with two worms 52, which mesh respectively with the worm wheels 51 on the spindles 49, so that by turning the said shaft by means of the hand wheel 54, the spindles will be rotated or turned so as to force the guide rolls 47 against the opposite sides of the rim of the wheel, and hold them there by a pressure which may be increased or diminished by turning the hand wheel.

In the operation of the mill, a blank approximating the shape of a wheel is placed on the mandrel 4 and the latter with the wheel therein is inserted in the mill. The drive rolls 5 are then moved inwardly until they are in contact with the inner side of the rim of the wheel; the tread roll is moved into contact with the tread of the blank, and the guide rolls into contact with the opposite sides of the rim. If when the parts are thus assembled the drive shaft 29 be started, the gears 27 will be rotated, thus rotating the two shafts 6 and their main rolls 5. The rotation of these rolls, rotates the wheel blank, and the contact of the latter with the tread roll 29 and guide rolls 47 causes them to turn. As the operation continues, the several rolls are gradually and slowly fed toward the blank thus compressing and rolling the rim into its final and finished shape.

The large bevel gears 27 from which the rolls 5 are driven, are placed with their axes vertical and serve as idler gears through which the power is transmitted from the driving gears 28 on the main shaft 29, to the gears 26 attached to the rolls 5, thus dispensing entirely with universal joints.

It is evident that many slight changes might be resorted to in the relative arrangement of parts shown and described without departing from the spirit and scope of my claims. Hence I would have it understood that I do not wish to confine myself to the exact construction and arrangement of parts shown and described, but

Having fully described my invention what I claim as new and desire to secure by Letters-Patent, is:—

1. In a mill for finishing car wheels, the combination of a main roll to engage the inner face of the rim of the wheel, a shaft for said roll, a movable carrier for the shaft, an idler gear, the axis of the carrier being coincident with the axis of the idler gear, a gear on the roll shaft meshing with the idler gear, gearing meshing with the idler wheel for rotating same, and means engaging the roll shaft carrier intermediate its axis and the roll for forcing the roll against its work.

2. In a mill for finishing car wheels, the combination of an air idler gear, means for rotating the same, a rotating shaft having a limited lateral movement in the arc of a circle concentric with the axis of the idler gear, a roll on said shaft, a gear on the shaft and meshing with the idler gear, and means having connection with the said shaft intermediate the axis of the idler gear and the roll for forcing the latter into contact with and for moving it away from the wheel, a roll to engage the tread of the wheel and means for moving the said latter roll toward the wheel.

3. The combination with two idler gears, a driving shaft located above the latter, gear

wheels on said shaft and meshing with the two idler gears for rotating same, two housings mounted to be moved laterally toward and away from the work, the axes of the 5 housings being coincident with the axes of the idler gears, a shaft in each housing, a roll on each shaft, independent means engaging each housing intermediate its axis and the roll for forcing the latter toward the 10 work and a gear on each shaft also meshing with the said idler gears.

4. In a mill for finishing car wheels, the combination of the two housings each journaled at one end, a shaft mounted in each 15 housing, a roll and a gear wheel on each shaft, idler gears meshing with the gear

wheels on the shafts for rotating them, the axes of said idler gears being coincident with the journals of the housings, a screw engaging each housing intermediate its journal 20 and its roll and nearer the latter, and gearing for actuating the screws whereby the housing may be moved laterally toward and away from the work.

In testimony whereof, I have signed this 25 specification in the presence of two subscribing witnesses.

CLARENCE L. TAYLOR.
